UNITED STATES PATENT OFFICE.

CHARLES A. RANDALL, OF NEW YORK, N. Y.

ELECTRICAL TIME-STAMP.

SPECIFICATION forming part of Letters Patent No. 380,595, dated April 3, 1888.

Application filed September 7, 1886. Renewed March 3, 1888. Serial No. 266,107. (No model.)

To all whom it may concern:

Be it known that I, CHARLES A. RANDALL, a citizen of the United States, residing at New York, in the county of New York and State of New York, have invented new and useful Improvements in Electro-Mechanical Time-Printing Stamps, of which the following is a specification.

The present invention relates to that class of time-recording stamps in which the type-wheels are rotated by electro-mechanical means; and the invention consists in the combinations of devices hereinafter specified in the claims.

15 In the accompanying drawings, Figure 1 is a top view of a time-stamp embodying my improvements, some of the parts being removed to better show the arrangement. Fig. 2 is a side elevation of the electro-magnets, armatures, impression-pad, and means for transmitting motion to the type-wheels. Fig. 3 is a diagrammatic view of the various circuits, electro-magnets, clock, and circuit making and breaking devices on the type-wheels.

25 The reference-numeral 1 designates the frame or casing of a time-stamp, which has rotary type-wheels bearing marks or characters indicating time, as in the stamp heretofore proposed by me. It is understood that suitable 30 means are provided for inking these type-wheels, and as my present invention relates only to special means for periodically rotating these type-wheels and holding them locked at all other times I have not deemed it necessary 35 to illustrate all the parts which are common to the class of stamps to which my invention belongs.

The reference-numeral 2 designates the hour-wheel, which has secured to it at one side a 40 circuit-wheel, 3, provided with one contact-point, 3^a. Bearing upon this circuit-wheel is the contact-spring 5, which is so arranged that electrical contact is made between the contact-spring 5 and the metal point 3^a of the wheel 3 45 once every hour. Upon the opposite side of the hour-wheel 3 is secured a non-metallic pin, 4, a part of which slightly projects above the circumference of another circuit-wheel, 7, and passes in its revolution under the spring- 50 contact 6, lifting it at a certain position from the circuit-wheel 7. The latter is provided with a single contact, 7^a, and is secured to the

minute type-wheel, together with the escape- 55 ment-wheel 8, and a second circuit-wheel, 9, having a spring-contact, 10. The circuit-wheel 9 is constructed so that contact between it and the contact-spring 10 is maintained during fifty-nine sixtieths of a revolution, the contact being broken only one-sixtieth of a revolution. There are three positions of these circuit-wheels and contact-springs relative to each other: first, 9 and 10 being closed fifty- 60 nine sixtieths of a revolution, while 7 and 6 and 3 and 5 are broken; second, 9 and 10 being broken and 7 and 6 closed; third, 9 and 10 65 being broken, 7 and 6 being broken by the lifting of the spring 6 through the pin 4, and 3 and 5 being closed. These three positions of the contact devices give three distinct electric 70 circuits within the machine in an automatic manner, and for convenience I will call them the "minute-wheel circuit," the "hour-wheel circuit," and the "day-wheel circuit."

The operation and the circuits are as follows, 75 viz: The minute-wheel circuit being closed at twelve o'clock noon, the circuit-wheel 9 and contact-spring 10 are in contact, and the electric circuit is then (see diagram view) from the battery 11, wire 16 to the clock 12, and from the latter to the electro-magnet 13, wire 80 14, spring 10, wheel 9, and shaft 15 back to the battery. By means of a contact device and current-wheel on the clock-arbor, the electric current is caused to pass through the clock once per minute, and the electro-magnet is 85 energized at each impulse and works the minute-wheel around step by step, the fifty-ninth movement leaving the circuit-wheels attached to the minute-wheel in the position seen in Fig. 3--that is, the contact-spring rests on the 90 insulated point 9^a of the contact-wheel 9, and the spring 6 makes contact with the metal contact-point 7^a of the circuit-wheel 7, so that the circuit will be broken between 9 and 10 and closed between 7 and 6. The next elec- 95 trical impulse or current from the clock (the sixtieth) now passes over the wire 16, clock 12, magnet 13, wire 14^a, magnet 16, wire 17, spring 6, circuit-wheel 7, and shaft 15 back to the battery, thus energizing both electro-magnets 100 13 and 16, and working the hour-wheel 2 one step, and also the minute-wheel the sixtieth step. In this manner the circuit is again closed at 9 and 10 and broken at 7 and 6 for

fifty-nine minutes more, when the same operation is repeated, thus hourly moving the hour-wheel, step by step, one step an hour. On the twenty-third movement of the hour-wheel the 5 insulating-pin 4 passes under the spring 6 and raises it, so as to prevent contact between 7 and 6 for a specified period, and at the same time the contact-point of the circuit-wheel 3, attached to the hour-wheel, passes beneath the 10 contact-spring 5, making electrical contact therewith, and this happens only once in twenty-four-hours and only for one minute or thereabout. When the parts are in the position last mentioned, the circuit is from the 15 battery 11, wire 16, clock 12, electro-magnet 13, (9 and 10 being broken,) wire 14^a, magnet 16, (7 and 6 being broken,) wire 18, magnet 19, wire 20, spring 5, circuit-wheel 3, and shaft 15 back to the battery, thereby energizing 20 the electro-magnets 13, 16, and 19, when the day-wheel, the hour-wheel, and the minute-wheel are each moved one step, so that the minute-wheel is moved sixty times per hour, the hour-wheel once per hour, and the day-wheel once per day by the direct action of 25 electro-magnets automatically controlled by a circuit-closing clock attached to or in electrical connection with the time-recording stamp.

The minute, hour, and day wheels, combined 30 with the electro-magnets and contact devices in the above-described manner, are mounted upon the shaft 15 so as to rotate thereon, and each wheel has an escapement ratchet-wheel, 25, secured thereto. Feed dogs 35 or pawls 26, carried by lever-extensions 27 of the armatures 28 of the three electro-magnets 13, 16, and 19, serve to rotate the type-wheels periodically in the manner and at the times heretofore set forth.

40 It should be observed that the pull upon the armatures of the electro-magnets is not the direct cause of the movement of the type-wheels, since it is the action of springs which effects the rotation of the wheels, such provision being made by reason of the presence in the 45 stamp of a non-interfering mechanism designed to prevent the possible detention of the type-wheels by the act of printing. In time-recording stamps as heretofore made this is a very great defect, and I overcome the same by the 50 employment of a simple non-interfering mechanism, whereby the type-wheels are prevented from moving just at the instant of taking the impression, thus insuring clear and distinct 55 printing and at the same time not detaining the type-wheels sufficiently long to cause them to lose time or throw them out of unison with the clock-controller.

60 It will be observed that the electro-magnets 13 of the minute-wheel are energized for an instant once a minute and that the function of such magnets is to set the dog or pawl 26 of said minute-wheel ready for action and not to move the type-wheel by the pull of the electro-magnet upon the armature. On the contrary, 65 it is the spiral or other spring 30, connected with the armature lever and frame of the

stamp, which serves to actuate the dog and move the type-wheels. It is apparent, therefore, that the electro-magnet can act and set 70 the dog even though the type-wheels are held by the impression-pad being upon the same, and the action of the electro-magnet also serves to put tension upon the returning-spring 30, which of course remains under tension until 75 free to act. I therefore avail myself of this method of using the electro-magnet and spring and cause the latter to perform the work of turning the type-wheel, since it may be kept under tension for nearly a full minute, whereas 80 the force of the magnet is only instantaneous.

In connection with the armature-lever, spring, and ratchet-and-pawl feed mechanism I employ a simple locking device controlled by the impression-lever, which acts to hold the 85 escapement feed-lever while an impression is being taken, so that even though the electro-magnet may be energized just at the instant an impression is being taken there is no interference, as the feed-lever is locked and can only move in one direction when the impression-lever is away from the type-wheels. This locking device or non-interfering mechanism consists of two swinging arms, 40 and 41, of 90 which the latter rests upon the escapement 95 feed-lever. The arm 40 carries a pin or stud, 43, under which passes the projecting end of the impression-lever 45 or a hooked piece or arm, 46, projecting from the same. The function of the pin 43 and arm 46 is to raise the arm 100 40 away from the arm 41, as the impression-lever moves away from the type-wheels, and as the impression-lever descends the arm 40 is released from the hooked arm and rests upon the arm 41 at such an angle and in such relation to 105 it as to lock the arm 41 against the feed-lever when the armature is attracted to the magnet and hold all locked until the impression-lever returns to place. In other words, the arm 46 being rigid upon the impression-arm 45, it 110 will be seen that the depression of the outer end of the latter will disengage the hooked end of the arm 46 from the pin 43, thereby leaving the arm 40 resting upon the arm 41, the arm 41 resting upon the escapement feed-lever. While in this position the arm 41, 115 which is engaged with the end of arm 40, prevents action of the escapement feed-lever by bearing upon the latter until such time as the release of the impression-lever 45 again throws 120 the hooked end of the arm 46 under the pin 43 on the arm 40, and thereby raises the locking-arm 40 far enough to release the end of arm 41 and allow the spring 30 to act upon the latter to actuate the escapement feed-lever 125 after the impression has been made. In such manner the electro-magnet is permitted to act and set the dog 26 and to place tension upon the spring every minute, no matter what may be the position of the impression-lever, and at 130 the same time the type-wheel is permitted to turn every minute by the action of the spring, and also insuring clear and distinct printing. I have shown the locking mechanism as ap-

plied only to the minute-wheel escapement feed-lever; but it is evident that it must and can be applied to all of the feed-levers in some form.

- 5 The minute, hour, and day wheels are moved by electro-mechanical devices in the manner fully set forth in the foregoing description, and the month and year wheels 50 and 51 are also provided to complete the stamp. These wheels 10 50 and 51 are moved manually and are held by a locking-pin, 52. It will be understood that two or more printing-stamps of the type herein indicated may be located in the same electric circuit and combined with a single 15 circuit-controlling clock. It will also be understood that the electro-magnets of the apparatus may be controlled by actually making and breaking the circuit in other ways than shown, and also that all of the electro-magnets 20 may be included in one continuous circuit, and by proper means automatically shunted out and into said circuit at proper times without actually breaking the circuit, thus practically producing two or more circuits within the 25 machine, and without departing from the spirit of my invention, and I therefore do not limit myself to the devices as shown, nor to the actual making and breaking of each circuit.

I am aware of the existence of an electro-mechanical time-printing stamp in which an electro-magnet, through the intervention of mechanical devices, is made to move the type-wheel step by step by the direct action of the current. As an electro-magnet is charged and 30 discharged quickly, it is obvious that in the instrument above referred to all of the parts must be in condition and position to move directly by the action of the magnet, and at the 35 moment or instant of time that the magnet is charged, or otherwise the parts are not operated. If in such construction the impression-pad happens to be upon the type-wheels 40 at the instant the magnet is charged, the parts cannot move, and the instrument is thrown 45 out of unison with the clock and is behind one minute, and this defect renders the instrument useless for printing the correct time. In my instrument, however, the electro-magnet and its armature and armature-lever are always 50 ready for action, and if the printing-pad is upon the type-wheels at the instant the magnet 55 is charged the armature, armature-lever, and feed-dog may be operated and tension be put upon the spring without throwing the type-wheels, and upon releasing the type-wheels by

removing or liberating the printing-pad the tension of the spring will throw the type-wheel and present the next figure thereon, and in such manner the printing-wheels are always made to move in time with the clock, unless 60 willfully held for one minute, which, of course, would be abuse and not use of the instrument.

Having thus described my invention, what I claim is—

1. In an electro-mechanical time-recording 65 hand-stamp, the combination, with the electro-magnet, armature-lever, feed-pawl, and type-wheel, of the impression-lever, the swinging arms 40 and 41, pin 43, and arm 46, substantially as described.

2. In an electro-mechanical time-recording 70 hand-stamp, the combination, with the circuit-controlling clock, the minute, hour, and day type-wheels, and impression-lever, of the circuit-wheels 9, 7, and 3, the insulating-pin 4, 75 contact-springs 10, 6, and 5, independent electro-magnets 13 16 19, armature-levers, ratchet-wheels, feed-pawls, and retractile springs, substantially as described.

3. In an electro-mechanical time-recording 80 hand-stamp, the combination of the type-wheel or wheels, electro-mechanical devices for actuating the same, an impression-lever for taking an impression therefrom, and the non-interfering or locking mechanism 40 41 43 46, 85 controlled by the impression-lever, as and for the purposes set forth.

4. The combination, in an electro-mechanical time-printing stamp, of type-wheels, an electro-magnet and its armature, means for intermittently operating the same, a feed-lever having a pawl and a retractile spring secured thereto, an impression lever and pad, and a locking mechanism controlled by the impression-lever for locking the feed-lever and preventing the action of the retractile spring when the impression-lever is depressed, all constructed and relatively arranged substantially as set forth, whereby the force of the electro-magnet places tension upon the retractile 90 spring and the turning of the type-wheels is effected by the action of the spring when the feed-lever is free to move, as and for the purposes set forth.

In testimony whereof I affix my signature in 105 presence of two witnesses.

CHARLES A. RANDALL.
